US00D723567S

(12) **United States Design Patent**
Akana et al.

(10) **Patent No.:** US D723,567 S
(45) **Date of Patent:** ** *Mar. 3, 2015

(54) **COMPONENT OF AN ELECTRONIC DEVICE**

(71) Applicant: **Apple Inc.**, Cupertino, CA (US)
(72) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **Richard Hung**, San Jose, CA (US); **Minh Dinh**, San Jose, CA (US); **M. Evans Hankey**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Nicholas George LeBreton Merz**, San Francisco, CA (US); **Scott A. Myers**, San Francisco, CA (US); **Shin Nishibori**, Kailua, HI (US); **David A. Pakula**, San Francisco, CA (US); **Matthew Dean Rohrbach**, San Francisco, CA (US); **Peter Russell-Clarke**, San Francisco, CA (US); **Christopher J. Stringer**, Woodside, CA (US); **Tang Yew Tan**, San Francisco, CA (US); **Trent Weber**, Saratoga, CA (US); **Eugene Antony Whang**, San Francisco, CA (US); **Michael Benjamin Wittenberg**, Sunnyvale, CA (US); **Rico Zörkendorfer**, San Francisco, CA (US)

(73) Assignee: **Apple Inc.**, Cupertino, CA (US)

(*) Notice: This patent is subject to a terminal disclaimer.

(**) Term: **14 Years**

(21) Appl. No.: **29/448,239**

(22) Filed: **Mar. 11, 2013**

Related U.S. Application Data

(63) Continuation of application No. 29/376,052, filed on Sep. 30, 2010, now Pat. No. Des. 677,664.

OTHER PUBLICATIONS

Co-pending U.S. Appl. No. 29/384,916, Akana et al., "Component of an Electronic Device," filed Feb. 4, 2011 (not published).

Primary Examiner — Deanna L Pratt

(74) *Attorney, Agent, or Firm* — Sterne, Kessler, Goldstein & Fox P.L.L.C.

(57) **CLAIM**

The ornamental design for a component of an electronic device, as shown and described.

DESCRIPTION

FIG. 1 is a bottom front perspective view of a component of an electronic device showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The shade lines in the Figures show contour and not surface ornamentation.

The broken lines in the Figures show portions of the component of an electronic device which form no part of the claimed design.

1 Claim, 5 Drawing Sheets
